UNITED STATES PATENT OFFICE.

GEORGE F. VOIGHT, OF OAKLAND, CALIFORNIA.

LATH SPACER.

Application filed May 6, 1924. Serial No. 711,458.

To all whom it may concern:

Be it known that I, GEORGE F. VOIGHT, a citizen of the United States, residing at Oakland, in the county of Alameda and State of California, have invented new and useful Improvements in Lath Spacers, of which the following is a specification.

My invention relates to improvements in lath spacers particularly useful for attaching wire lath to the wall sheathing of stucco structures, although also useful for other purposes, and one of the objects of the invention is the provision of a sheet-metal spacing cap normally locked on the forward end of a nail but operatively slidable thereon for cooperating therewith for securing wire lath in outstanding relation to the wall sheathing of stucco structures.

A further object is the provision of a spacing cap having a horizontally disposed body portion supported at opposite ends by a pair of vertically extending leg members.

A still further object is the provision of a pair of opposed lath retaining humps or projections struck upwardly into the body portion of the cap, for holding the lath on the latter and underneath the nail head when the spacer is driven into its final position on the wall sheathing for securing the lath thereto.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a side elevation of one of my improved lath spacers disposed in engagement with the face of the wall sheathing of a stucco structure preparatory to driving it thereinto;

Figure 2 is a face view thereof;

Figure 3 is a view of one of the spacers after being driven into its permanent position on the wall sheathing, with a section of wire lath confined between the spacing cap and nail head, and a section of stucco composition supported by the lath;

Figure 4 is a view on line 4'-4', Fig. 2;

Figure 5 is a view on line 5'-5', Fig. 1;

Figure 6 is a top plan view of the spacer

as the same would appear driven into the wall sheathing with a section of lath seating on the spacing cap and engaged by the nail head, a portion of the nail head being shown broken away;

Figure 7 is a cross section on line 7'-7', Fig. 1;

Figure 8 is a view on line 8'-8', Fig. 1;

Figure 9 is a view on line 9'-9', Fig. 2;

Figure 10 is a bottom plan view of the spacing cap and a cross sectional view of the nail shank;

Figure 11 is a perspective view of the spacing cap removed from the nail shank;

Figure 12 is a face view of a blank stamping from which the spacing cap is formed.

Referring to the drawings in detail, throughout which like reference characters designate like parts:

The numeral 1 designates the wall sheathing of a stucco structure, which comprises ordinary boards nailed preferably in close jointed order across the face of the frame timbers of the walls and such other portions of the structure intended to receive an outer coating of stucco composition, and is provided on its face side with a course or layer of building paper 2. The building paper being intended to prevent exterior moisture from penetrating to the wood-work of the structure.

3 designates my improved lath spacer, which comprises a spacing cap 4 and a fastening nail 5, the latter embodying the usual cylindrical shank 6 and flattened head 7.

The spacing cap 4 is formed of sheet-metal and comprises an intermediate body portion 8, which is circumferentially circular and disposed in a plane at right angles with the axis of the shank 6 and has a central opening 9, around the margin of the lower side of which is a downwardly projecting sleeve 10, and a pair of diametrically opposed supporting legs 11. The latter are arcuated in cross section and their lower ends are struck outwardly to provide seating lips 12 having their outer edges curved slightly upwards.

13 designates a pair of inverted V-shaped slits or spaces between registering edges of the legs 11, the object of which being to provide, first, entrance means through which the plastic stucco may be spread to fill the interior of the cap, and second, to facili-

tate the upwardly kicking of the metal in forming the retaining humps or projections 14.

The projections 14 are formed at the 5 margin of the body portion 8 in vertical alignment with the slits 13, and are intended, primarily, as means for limiting the lateral movement of the lath wire 15 in one direction on said body portion, and second, 10 as means for strengthening the body portion in cross section between the legs 11.

The lower or forward end of the shank 6 is intended to project normally a short distance down through the opening 9 and sleeve 15 10, and the relative diameter of the shank with the opening 9 and the inside diameter of the sleeve 10, is intended to be such that the shank will fit sufficiently tight therein so that the spacing cap will be normally 20 locked on the shank against vertical movement in either direction relative thereto, but vertically slideable thereon in the direction of the head 7, when the forward movement of the spacing cap is arrested by its engagement 25 with the face of the wall sheathing into which the shank 6 may be operatively forced a proper distance.

The object of the sleeve 10 is to prevent 30 expansion of the opening 9 when the shank 6 is forcibly projected therethrough, as when initially placing the spacing cap on the shank. It also acts as a side brace for holding the shank in axial alignment with the spacing cap during handling of the spacer 35 as when disposing it in position on the wall sheathing preparatory to driving it therewith.

The purpose of the lips 12 is to provide 40 the lower ends of the legs 11 with comparatively broad seating areas for engagement with the building paper 2, which the unprotected edges of the thin sheet-metal from which the legs are formed would be likely to cut and damage if the lips were not provided. The lips also provide the legs with a certain amount of rigidity.

The spacer is applied for securing the 50 lath 15 by hooking one of the humps or projections 13 under one of the wires of the lath, with the forward end of the shank 6 disposed in engagement with the face of the sheathing 1 (see Fig. 2.), and then driving the nail forwardly into the sheathing against the frictional resistance set up by the binding of the shank against the margin 55 of the opening 9 and the walls of the sleeve 10.

It is obvious that in case two of the wires forming the lath 15 are disposed in sufficiently close parallel relation, a wire may be disposed on each side of the shank 6 and the two bound down on the body portion 8 by the hand 7.

I claim:

65 1. In a lath spacer, a spacing cap includ-

ing a pair of oppositely disposed supporting legs hollowed in cross section on one side and provided at their lower ends with outwardly projecting lips.

2. In a lath spacer, a spacing cap formed 70 of a strip of metal having its ends bent downwardly to form a pair of legs, said legs concavo-convex in cross section and provided at their lower ends with outwardly projecting lips, the outer margin of said 75 lips arcuated in a horizontal plane.

3. A lath spacer comprising, a spacing cap embodying a body portion provided at each end with a supporting leg, said legs arcuated in cross section and having their free 80 ends curved outwardly, and a nail disposed between said legs and projecting through said body portion.

4. A lath spacer comprising, a spacing cap comprising a body portion having at 85 each end a downwardly projecting supporting leg and intermediate its ends a pair of retaining humps, said humps disposed in a plane extending between said legs, and a nail projecting vertically through said body 90 portion approximately equi-distant from said legs, the head of said nail adapted to engage and bind a lath wire on said body portion between said nail and one of said 95 humps when said nail is operatively driven a proper distance into the support against which the spacing cap is seated.

5. In means of the character described, a spacing cap embodying a body portion disposed in a horizontal plane and provided 100 with a central opening, supporting legs projecting downwardly from said body portion, and a pair of retaining humps projecting upwardly from said body portion, said supporting legs and the axis of said opening disposed in the same vertical plane, said 105 retaining humps disposed in a vertical plane extending through said axis at right angles with said first named vertical plane.

6. In a lath spacer, a spacing cap formed 110 of a strip of metal bent intermediate its ends to form a pair of opposed downwardly projecting legs, an outwardly projecting lip on the lower end of each of said legs, the side margins of upper portions of said legs converging and intersecting on registering 115 sides in the form of arches, the apexes of which forming wire retaining projections disposed in a plane at right angles with the plane of said legs.

7. A lath spacer comprising, a spacing cap formed of a strip of sheet metal having opposite ends bent downwardly to form a pair of opposed supporting legs, and a cooperating nail projecting centrally through said spacing cap between said legs, said legs curved in cross section along a plane extending approximately parallel with the periphery of said nail, the free ends of said 125 legs disposed apart from each other, the op- 130

posite ends of said legs intersecting at their edges.

8. A lath spacer comprising, a spacing cap formed of an oblong strip of sheet metal, the ends of said strip of metal bent downwardly along horizontal curves thereby forming a pair of opposed supporting legs arcuated in cross section, the free ends of said legs spaced apart from each other, 10 registering edges on the opposite ends of said legs converging into upwardly projecting retaining humps, and a nail extending through said spacing cap between said legs.

9. In a lath spacer, a spacing element 15 formed of a strip of metal bent intermediate its ends to form a pair of downwardly projecting legs, said legs hollowed in cross section on one side and provided at their lower ends with outwardly projecting lips, the upper 20 end of the spacing element provided with an opening, means projecting downwardly from the margin of said opening, and a nail projecting axially through said opening and engaging said means, said 25 means adapted for holding said nail in axial alignment with the spacing element.

10. In combination, a spacing element formed of a strip of metal bent intermediate its ends thereby forming a pair of opposed, 30 downwardly projecting, legs, said legs hollowed on one side and provided at their lower ends with lips, the upper end of said spacing element having a central opening

provided at its margin with downwardly projecting means arcuated in a horizontal 35 plane, and a nail projecting vertically through said opening, said means adapted to engage opposed sides of said nail for limiting lateral tilting thereof relative to the spacing element, portions at the upper 40 end of said spacing element on opposite side of said nail struck upwardly thereby forming wire retaining projections, said legs disposed in a plane at right angles with the plane of said projections. 45

11. In a lath spacer, a spacing element formed of a strip of metal bent intermediate its ends thereby forming a pair of opposed legs, registering edges of which converging towards their upper ends and intersecting 50 in the form of an arch, the apex of said arch forming an upwardly extending wire retaining means, and a headed nail projecting vertically through said spacing element, the head of said nail adapted to operatively 55 engage and bind a wire on the upper end of said spacing element against one side of said nail and along the inner side of said means, said nail and means disposed in a plane at right angles with the plane of said legs, the lower ends of said legs spaced a distance apart. 60

In testimony of the foregoing being my own, I have hereunto affixed my signature this 30th day of April, 1924.

GEORGE F. VOIGHT.
